UNITED STATES PATENT OFFICE.

WASHINGTON IRVING BABCOCK, OF NEW YORK, N. Y.

ANCHOR FOR VESSELS.

No. 902,046.

Specification of Letters Patent.

Patented Oct. 27, 1908.

Application filed December 19, 1907. Serial No. 407,129.

To all whom it may concern:

Be it known that I, WASHINGTON IRVING BABCOCK, a resident of and whose post-office address is 40 Franklin Place, Flushing, in the county of Queens and city and State of New York, have invented a new and useful Improvement in Anchors for Vessels; and I do hereby declare that the following is a full, clear, and exact description of the same.

10 My improved anchor belongs to that class of anchors known as stockless, consisting only of a shank, head and ring, without any stock, and therefore adapted to be pulled up by the anchor cable attached to the ring 15 against the side of the bow of the ship and carried in that position, the shank extending up into the hawse pipe and the head being outside. The anchor is then ready to be let go or dropped overboard at short notice 20 without the necessity or raising it off the deck, where a stocked anchor must be carried when not in use. The ordinary and usual form of stockless anchor has the head made in the general shape of a cross bar 25 with two flukes, hinged to the end of the shank in various ways so as to allow the flukes to swing out from the shank a certain distance on either side to form a hook, the flukes then entering the ground and oppos- 30 ing a resistance against the pull of the cable, which is the essence of the device. The head has projections made on it in various ways so that whichever side of the head falls underneath the projections will catch the 35 ground and act to trip the head and swing the flukes down so that they will enter the ground. Necessarily, therefore, the part of the anchor projecting from the hawse hole when the anchor is drawn up and not in use, 40 that is, the head and flukes, is of an irregular shape with many sharp corners and angles. When a ship is being moved around docks and other ships, this head is very liable to foul and catch on the docks and spiles or on 45 other vessels, frequently being broken itself or causing damage to whatever it touches. In collisions between vessels under way also, the heads of these stockless anchors have frequently caused great damage, the anchor 50 of one ship penetrating the side of the other ship and ripping through it for a greater or less distance. Particularly is this so in glancing collisions. Hawsers and lines are also liable to catch on and become fast to it. 55 Further, this head being of an irregular shape

and therefore only imperfectly covering up the hawse hole offers but little obstruction to the entrance of water when the vessel is among waves, and as it is difficult to fit a tight cover or buckler over the inner end of the hawse pipe on account of the chain cable passing through there, many cases have occurred where much water has entered the ship through the hawse pipe in a storm and vessels have been lost from that cause alone. 65

My improved anchor was designed to avoid these objections and consists, generally speaking, of a head formed of a deep-dished circular plate connected to the shank by a ball and socket or other universal joint 70 so that the shank will pass through the hawse pipe and the head will serve as a hawse buckler closely to cover the hawse hole in whatever position the anchor comes up. 75

In order that my invention may be fully understood, I shall first describe in detail the mode in which I carry the same into practice and then particularly define the invention in the claim.

Reference is to be had to the accompanying drawing forming part of this specification in which

Figure 1 is a perspective view of an anchor embodying my invention when resting on the bottom; Fig. 2 is a sectional view of said anchor indicating the shank in the hawse pipe and the head covering the hawse hole; Fig. 3 is a view of the outside of the head of the anchor. 85

In the drawing 10 is the shank of the anchor; 11 is the ring to which the cable is to be attached and 12 is the head of the anchor. To connect the shank 10 universally to the head 12 I, by preference, form the end of the shank with a ball 13 and the head 12 with a 90 socket 14, in which the ball 13 is fitted to work universally through a certain limited angle. The ball 13 is retained in the socket 14, preferably, by means of a correspondingly shaped annular plate 15 attached to the head 12. The head 12 is made in the form of a deep-dished circular plate so that when the shank 10 is drawn through the hawse pipe, as indicated in dotted lines in Fig. 2, the head 95 will act as a hawse buckler closely to cover the hawse hole and prevent water from entering therein. The universal joint permits the head to adjust itself closely against the side of the vessel in whatever position the anchor comes up, as indicated in Fig. 2. The 100 105 110

outside of the head is, by preference, made partly in the form of a frustum of a cone, so that when it is dropped on the bottom and tension is put upon the shank 10 by the cable, the edge of the head will be sure to catch the bottom and upset or tip the head into position substantially as shown in Fig. 1, thereby taking a firm hold on the bottom. The outer part of the head, as well as that of the 5 retaining plate 15 is made rounded as shown so that, the ball 13 being also rounded, there will be no projections on the outside of the head to foul or catch on docks or spiles or other vessels or on hawsers or lines, as herein 10 before set forth.

15 Having thus described my invention and

the manner in which I carry the same into practice, I claim as my invention:—

A combined anchor and hawse buckler for vessels consisting of a head formed of a 20 dished circular plate adapted to cover and close the hawse hole and also to catch on the bottom, and a shank connected by a universal joint to said head, substantially as shown and described.

25 In testimony whereof I have hereunto set my hand the 17th day of December 1907.

WASHINGTON IRVING BABCOCK.

In presence of—

CLARENCE L. BURGER,
Z. F. PHELPS.
